UNITED STATES PATENT OFFICE.

GUS SCHALLER, OF ST. LOUIS, MISSOURI.

DESIGN FOR A SEESAW.

58,506.

Specification for Design.

Patented July 26, 1921.

Application filed March 10, 1921. Serial No. 451,300. Term of patent 14 years.

To all whom it may concern:

Be it known that I, Gus SCHALLER, a citizen of the United States, residing at St. Louis, in the county of St. Louis and State of Missouri, have invented a new, original, and ornamental Design for a Seesaw, of which the following is a specification, reference being had to the accompanying drawing, forming part thereof.

The figure is a perspective view of a seesaw showing my new design.

I claim:

The ornamental design for a seesaw, as shown.

GUS SCHALLER.
